FOOT MANIPULATING APPARATUS

John H. McCahan, Canton, Louis J. Fuller, Massillon, and Herman L. Samblanet, Canton, Ohio, assignors to Foot Norm Inc., Canton, Ohio, a corporation of Ohio

Application January 27, 1934, Serial No. 708,626

12 Claims. (Cl. 128—61)

The invention relates to apparatus for exercising, flexing and massaging the human foot in such manner as to strengthen, build up and restore the ligaments thereof, as well as the fascia, 5 blood vessels and nerves of the foot, and the muscles and tendons acting thereon, and more particularly, to restore the bones and cartilages of the foot to their natural positions.

The greater proportion of the painful and irritating ailments of the feet can be traced directly 10 either to the more or less tightly fitting shoes and the like, which are universally worn by all civilized peoples, or to trauma or sickness.

Due to any of the above causes, the bones of the 15 feet are cramped or forced out of natural position, so as to preclude the natural movements thereof in supporting the weight of the body, causing the ligaments, fascia, blood vessels and nerves investing the bones, and the muscles and tendons acting 20 upon the same to become stiff and/or atrophied, resulting in deformed and painful feet, crooked toes, bunions and other kindred ailments.

We have discovered that by treating a foot in 25 an apparatus constructed according to the present invention, which apparatus is adapted to flex, massage and thoroughly exercise all of the bones of the foot, together with all the muscular tissues affecting the same, the foot will become relaxed and pain is relieved; and that continued 30 use of the apparatus will restore the bones to their natural positions and build up and strengthen all of the various members in and relating to the foot, and also that muscles, nerves and reflex actions in all parts of the body are greatly 35 benefited.

Accordingly, it is an object of the present invention to provide an apparatus adapted for manipulating substantially all parts of the foot simultaneously.

Another object is to provide an apparatus having single operating means for simultaneously manipulating substantially all parts of the foot.

Another object is to provide a foot manipulating apparatus which is adjustable for various sizes of feet.

A further object is to provide means for flexing the rear portion of the foot in one direction, while the front portion is flexed in the opposite direction.

A still further object is to provide means for securely maintaining the foot as a whole in position while the different portions thereof are being flexed or manipulated.

Another object is to provide means for massag-

ing various parts of the foot as the foot is being manipulated.

A further object is to provide flexible supporting means adapted for supporting substantially the entire foot, and capable of being twisted to 5 flex the foot in different directions.

The foregoing and other objects are embodied in the relatively simple and compact construction comprising the present invention, which is easily applied to the foot and which may be manipulated by an unskilled or inexperienced person to give the desired beneficial results.

In general terms, the improved construction comprising the present invention, includes, a base, a frame universally mounted at the front end 15 of the base, an operating handle secured to the frame, a plurality of flexible foot-supporting strips secured at one end to said frame, means for slidably supporting the other ends of said strips at the rear end of the base, a resilient pad 20 supported on said strips, a heel support independently and longitudinally adjustably supported on the base above the strips and between the frame and the rear strip support, said heel support being movable transversely of the frame, and means 25 operatively connecting the heel support and frame for imparting transverse movement to said heel support.

Referring to the drawings forming part hereof.

Figure 1 is a side view of the improved apparatus, partly in section and partly in elevation, showing a foot secured in position thereon for manipulation;

Fig. 2 is a plan view thereof showing the foot in dot-dash lines;

Fig. 3 is a plan view of the apparatus showing the various foot securing means disconnected and parts being broken away;

Fig. 4 is a fragmentary plan view showing the manner of applying auxiliary strapping or securing means for treating particular parts of the foot;

Fig. 5 is a fragmentary end view of the foot-supporting strips, showing the method of connecting an auxiliary strap thereto;

Fig. 6 is a fragmentary longitudinal sectional view as on line 6—6, Fig. 3, showing a portion of the foot in dot-dash lines;

Fig. 7 is a fragmentary transverse sectional view as on line 7—7, Fig. 1, with the foot re- 50 moved;

Fig. 8 is a fragmentary transverse sectional view as on line 8—8, Fig. 1;

Fig. 9 is a fragmentary transverse sectional view as on line 9—9, Fig. 3; and

Fig. 10 is a fragmentary transverse sectional view as on line 10-10, Fig. 3.

Similar numerals refer to similar parts throughout the drawings.

5 The improved apparatus includes a base indicated generally at 11, having a front leg 12 and a rear leg 13 for being supported on the floor and the like. The leg 12 is preferably somewhat longer than leg 13, so that the base plate 14 is disposed at an angle to the supporting floor or the like.

10 A foot-supporting frame indicated generally at 15 is universally mounted on the front end of the base plate 14 by means of a ball and socket joint indicated generally at 16. Preferably, the frame 15 is provided with a spherical boss 17, constituting the ball of the joint and supported on a spherical seat provided on the tubular member 18, constituting the socket of the joint, which 15 tubular member is secured to the base plate 14 in any suitable manner.

15 Means for yieldably holding the ball and socket in interfitting relation to permit universal movement of the frame 15 relative to the base 11 includes a bolt 19 secured at its upper end to the boss 17, and extending through the tubular member 18 and the base plate 14. A washer 20 surrounds the bolt 19 and abuts the underside of the base plate, and a wing nut 21 is provided on the lower end of the bolt 19. A coil compression 20 spring 22 is preferably interposed between the washer 20 and the nut 21 for yieldably holding the boss 17 against the spherical seat of the socket 18.

25 The frame 15 preferably includes the side members 23 and 24 connected at their front ends by the transverse member 25. An upright handle rod indicated generally at 26 may be screwed in the central portion of the transverse member 25 for providing means whereby the frame 15 may be manually moved in any direction. The handle rod 26 preferably has a hand grip 27 on its upper end, and is made adjustable in length, as by having the rod include telescoping sections 28 and 29 which may be clamped in adjusted 30 position by a hand nut 30, all as shown in Fig. 1.

35 The rear ends of the side members 23 and 24 of the frame 15 preferably are connected by a transverse foot-supporting member 31, and the spherical boss 17 forming part of the ball and socket joint 16, is preferably formed on the transverse member 31.

40 The rear end of the base plate 14 for a purpose to be hereinafter described. A plurality of resilient metal foot-supporting strips 33 extend from the frame 15 rearwardly to and through the stationary support 32 for supporting substantially all of a foot, and are arranged in side by side preferably parallel relation and spaced apart laterally. These 45 strips 33 are preferably secured to the transverse member 31 of the frame 15 at their front ends, and are slidably mounted or supported at their rear ends in the stationary support 32, as by extending through slots 34 provided in a top plate 35 detachably secured to the support 32, as best shown in Figs. 1 and 10.

50 The transverse foot-supporting member 31 is preferably notched as shown at 31a for a purpose to be described, and the upper surface of member 31 is provided with laterally spaced 55 guides or slots indicated at 36 in Fig. 9, for receiving the strips 33. For the purpose of strengthening the strips 33 the slots 36 may be made deep enough to each take two strips, and

each slot provided with a resilient strip 33' superimposed upon and overlapping the front ends of the strips 33, as shown in the drawings.

60 As shown in Figs. 3 and 6, the front ends of the strips 33 may terminate at the notched portion 31a of transverse member 31, while the front ends of strips 33' extend forward therefrom to a position adjacent the member 25 and the rear ends of the strips 33' extend a short distance rearwardly of the rear edge of the 65 transverse member 31.

65 As shown in the drawings, the foot-supporting strips 33 may be five in number and centrally located with respect to the frame 15, and the frame 15 may be made wide enough to accommodate an extra strip 33'' in a slot 36' at each side of the strips 33, for the purpose of providing a wide support for the toes of the foot.

70 The strips 33 and 33' and 33'' are preferably secured in the slots 36 and 36' of transverse foot 75 supporting member 31 by means of a plate 37 fitting across the top of transverse member 31 and clamping the strips in their slots by means of screws 38 located between the slots and screwed into the transverse members 31.

75 A heel support indicated generally at 49 is independently and longitudinally adjustably mounted on the base plate 14 by means of the upright L-shaped supporting frame 41 which is provided with a longitudinally extending rib 42 80 slidable in a longitudinal slot 43 in the base plate. Means for clamping the frame member 41 in adjusted position on the base plate 14 to accommodate different sizes of feet may include a bolt 44 extending through the rib 42 and provided 85 with a clamping nut engaging the underside of the base plate 14, a lock nut 46, and a cam lever 47 pivotally connected to the upper end of the bolt 44 and abutting a plate 48 which engages the upper side of the frame member 41 for 90 clamping the frame member against the base plate 14.

95 Preferably, the frame member 41 has mounted thereon, a heel support mounting plate 50 which is pivoted at its lower end on a bolt 51 secured 100 to the frame 41, for transverse movement relative to the base. The heel support mounting plate is preferably provided with arms 52 extending upwardly around the outer strips 33, and a cup-shaped heel supporting member 53 is secured to 105 the upper ends of the arms 52 and located above the plates 33 between the frame 15 and the stationary support 32. Preferably, the heel supporting member 53 is shaped to substantially conform to the contour of the human heel.

110 Means for operatively connecting the frame 15 to the heel support 49 preferably includes a rod 56 pivotally connected at its front end to a stud 57 secured in the transverse foot-supporting member 31 substantially in the same horizontal 115 plane as the center of rotation of boss portion 17, and the rod 56 extends through the heel plate 50 and the upright heel supporting frame 41.

120 The rod 56 is pivotally connected to stud 57 by means of a substantially horizontal pivot pin 57a permitting relative movement of member 31 and rod 56 in a substantially vertical plane, and causing axial rotation of the rod 56 when the member 31 is rocked in a transverse plane.

125 The plate 50 is provided with a U-shaped opening 58 through which the rod 56 extends, and a substantially circular cam member 60 is keyed to the rod as at 61, the rod 56 being located 130

through an aperture 62 in the cam, which aperture is eccentric thereof.

The sides of the U-shaped opening 58 are preferably grooved as indicated in Figs. 1 and 7, and the sides of cam 60 fit loosely in said grooves. Accordingly, a transverse reciprocatory movement of the frame 15 will rotate the rod 56 and cam 60 so as to oscillate the heel plate 59 and its heel supporting member 53 about pivot 51 in 10 a transverse direction opposite to the direction of transverse movement of the foot-supporting frame 15.

A flat flap 64 of leather and the like is located upon the resilient strips 33, the front portion of the flap substantially conforming in size and shape to the foot-supporting member 31 of the frame 15 and being secured thereto as by screws 65 and by two or more of the screws 38, which are secured in the transverse member 31.

20 The rear portion of the flap 64 terminates in front of the top plate 35 of the stationary support 32, and between the top plate 35, and the member 31, the flap is preferably of a width sufficient to cover all of the strips 33.

25 At the upper side of its front portion and located over the member 31, the flap 64 is preferably provided with a yielding pad 66, which is suitably rounded for engaging under the transverse arch of a foot F supported on the apparatus, as best shown in Figs. 2 and 6. The pad 66 may be secured to the flap 64 in any suitable manner as by stitching.

30 A strap 68 is provided for securing the front portion of the foot to the frame 15 and for pressing the foot onto the pad 66. The strap 68 is connected at one end to one of the side members of the frame 15 by providing a button stud 69 on member 23 for example, and providing a snap-on button 70 on one end of the strap for connection with said stud.

40 The other end of the strap 68 is adjustably clamped to side member 64, as by a clamp indicated at 71, and the button stud 69 and clamp 71 are located at opposite sides of the transverse member 31. The strap 68 is adapted to fit over the transverse arch of the foot F, securing the foot to the frame 15 and pressing the transverse arch of the foot downwardly against the pad 66.

45 A preferably elastic strap 72 is provided for holding the toes of the foot F down against the strips 33' and the front portion of the flap 64, which lies over the supporting member 31. The strap 72 is provided at its ends with snap-on buttons 70, for fitting on the outer ends of button studs 69' provided on side members 23 and 24 in front of button stud 69 and clamp 71 respectively.

50 Preferably, the studs 69' are made longer than stud 69 for a purpose to be described. A button stud 69'' may be mounted on each of the members 23 and 24 in front of the studs 69' for a purpose to be later described.

55 Preferably, a short strap member 73 is connected to the central portion of strap 72 by a snap-on button and looped around the strap 68, for holding the straps 68 and 72 from sliding longitudinally on the foot when the same is being manipulated.

60 For securely holding the foot F in position on the apparatus with the heel of the foot supported in heel supporting member 53 of heel support 40 and the front part of the foot supported on frame 15, a pair of preferably elastic straps 74 is provided. Each of the straps 74 is secured at one end to the underside of the front

portion of the flap 64 at a position substantially under the pad 66, as by stitching or the like.

The other end of each strap 74 is provided with a snap-on button 70, or preferably with a series of snap-on buttons 70 located at intervals on the end portion of the strap. The rear walls of the heel supporting member 53 are provided with button studs 69a for connection with the snap-on buttons 70 on the straps 74.

65 When it is desired to secure a foot F in position 10 on the apparatus, the heel support 40 is first adjusted longitudinally to bring the ball of the foot substantially opposite to the clamp 71 and the pad 66 directly under the transverse arch of the foot. The heel support is then clamped by 15 means of the clamping lever 41 in the manner previously described. The strap 68 is then clamped tightly over the transverse arch, and the elastic strap 72 is connected at its ends to the studs 69' and at its central portion to the 20 short strap 73.

70 Each strap 74 is then led upwardly around and over the instep and back to the opposite side of the heel member 53 so that the straps 74 cross on the top of the instep. The straps 74 are then 25 stretched tightly enough to hold the foot securely in position and connected to the heel member 53 by means of the snap-on buttons 70 nearest the studs 69a.

75 When the foot is thus secured in position on 30 the apparatus, the resilient strips 33 are adapted to directly support the underside of the foot between the heel and toes thereof as the foot is manipulated by means of the hand grip 27.

The foot is manipulated preferably by moving 35 the hand grip 27 in a substantially circular path, so that during the transverse portions of the path the frame 15 is rocked transversely to oscillate heel member 53 in a transversely opposite direction. Transverse movement of the frame 15 40 bends and twists the resilient plates in such a way as to flex, massage and exercise the front portion of the foot and flex and exercise the heel portion of the foot in the opposite direction.

80 During the bending and twisting of the resilient 45 plates by movement of the frame 15, the slots 34 allow the rear ends of plates 33 to cant laterally to a slight extent and also to move back and forth longitudinally in said slots so as to prevent possible breakage of the plates 33.

85 During the forward and backward movements of the hand grip 27 the longitudinal arch of the foot is more particularly flexed, massaged and exercised by the bending and twisting of the plates 33, and this movement also acts to press 55 the pad 66 upwardly against the transverse arch, so as to massage the same.

90 If the longitudinal arch of the foot requires special treatment, because of a weakened condition or for any other reason, a yielding arch pad 60 75 may be positioned under the longitudinal arch of the foot, in a manner shown in Figs. 1 and 7. This arch pad preferably rests upon the flap 64 and is provided with clips 76 extending around the outer edge of the flap 64 and adapted to engage between adjacent strips 33 for holding the pad in position thereon.

95 Thus, when the arch pad 75 is used and the handle 26 manipulated, the movement of the strips 70 33 and the heel support 53 acts to massage the longitudinal arch of the foot for exercising and strengthening the same.

100 Manipulation of the foot, as above described, exercises, flexes and massages substantially all 75

parts of the same simultaneously in such manner as to strengthen, build up and restore the ligaments, fascia, blood vessels and nerves thereof, and the muscles and tendons acting thereon, resulting in a restoration of the bones of the foot to their natural positions. Moreover, the treatment of the foot in the improved apparatus affects all parts of the body to the extent that the various muscles, nerves and reflex actions throughout the body are greatly benefited. Obviously, the above described manipulation of the foot can be carried out by an inexperienced person.

For treating special ailments of and pertaining to the toes of the foot, auxiliary straps are provided.

In Fig. 4 is shown the manner of strapping the large toe for treatment of a bunion thereon, and also the method of strapping the second toe for treatment of a cramped condition such as "hammer toe."

A strap 78 is provided for the large toe, and has at one end a snap-on connection 79 adapted to fit down over the shank of either of the elongated button studs 69'. The other end of the strap is provided with an enlarged or beaded portion 80 for fitting between two of the strips 33' as shown in Fig. 5, so as to connect the other end of the strap to the strips 33'.

30 A slightly longer strap 81 is provided for correcting "hammer toe", and has at one end a snap-on connection 79 for fitting over the shank of either of the studs 69' and an enlarged or beaded portion at the other end for being secured between two of the strips 33'.

The enlarged or beaded ends of the auxiliary straps are adapted to fit within the notched portion 31a of the transverse member 31, if required by the position of the toes on the frame 15.

40 As shown in Fig. 4, the inner end of the strap 81 may be positioned between the first and second toes with its enlarged end connected between the two adjacent strips 33', and led upwardly therefrom over the second toe, down between the second and third toe and between another pair of strips 33', under the adjacent strip 33' and thence upward between the next two strips 33' and then out for connection with one of the studs 69'.

After the auxiliary straps are positioned as shown in Fig. 4, the strap 72 may be connected to the outer ends of studs 69' for holding all of the toes in position.

Obviously, the straps 14, 68 and 72 are adapted for securing either the right or left foot in position for being manipulated, and the auxiliary straps are reversible for treating the toes of either foot.

The button studs 69'' are provided for connection to any of the auxiliary straps which may be provided for various treatments of the toes.

We claim:

1. Foot manipulating apparatus including a base, a foot-supporting frame universally mounted on the base, a heel support mounted for transverse oscillatory movement on the base, and means operatively connecting said frame to said heel support for imparting transverse oscillatory movement to said heel support when the frame is given a transverse reciprocatory movement relative to the base.

2. Foot manipulating apparatus including a base, a foot-supporting frame universally mounted on the base, a heel support mounted for transverse movement on the base, and means

operatively connecting the frame and the heel support for imparting transverse movement to the heel support in a direction opposite to transverse movement applied to said frame.

3. Foot manipulating apparatus including a base, a foot-supporting frame mounted for transverse movement on the base, a heel support independently mounted for transverse movement on the base, and means operatively connecting said frame to said heel support for moving the heel support transversely when the frame is moved transversely.

4. Foot manipulating apparatus including a base, a foot-supporting frame universally mounted on one end of the base, a heel support spaced from the frame longitudinally of the base and independently mounted on the base for transverse movement in a plane perpendicular thereto, and means operatively connecting said frame to said heel support for moving the heel support transversely by moving the frame transversely.

5. Foot manipulating apparatus including a base, a foot-supporting frame universally mounted on one end of the base, a heel support spaced from the frame longitudinally of the base and independently and longitudinally adjustably mounted on the base for transverse movement in a plane perpendicular thereto, and means operatively connecting said frame to said heel support for moving the heel support transversely by moving the frame transversely.

6. Foot manipulating apparatus including a base, a foot-supporting frame universally mounted on one end of the base, a heel support spaced from the frame longitudinally of the base and independently mounted on the base for transverse movement in a plane perpendicular thereto, means for securing a foot in position on said frame and said heel support, and means operatively connecting said frame and said heel support for moving the heel support transversely by moving the frame transversely.

7. Foot manipulating apparatus including a base, a foot-supporting frame universally mounted on one end of the base, a heel support spaced from the frame longitudinally of the base and independently and longitudinally adjustably mounted on the base for transverse movement in a plane perpendicular thereto, means for securing a foot in position on said frame and said heel support, and means operatively connecting said frame and said heel support for moving the heel support transversely by moving the frame transversely.

8. Foot manipulating apparatus including a base, a frame universally mounted on one end of the base, a stationary support on the other end of the base, and a resilient foot-supporting strip extending between the frame and the stationary support and having one end secured to the frame and the other end slidably mounted in said stationary support, whereby movement of the frame will flex the resilient strip, said resilient strip being adapted to directly support the underside of the foot.

9. Foot manipulating apparatus including a base, a frame universally mounted on one end of the base, a stationary support on the other end of the base, a resilient foot-supporting strip having one end secured to the frame and the other end slidably mounted in said stationary support, a heel support longitudinally spaced from said frame and independently mounted on the frame for transverse movement in a plane

perpendicular thereto thereof, said heel support being disposed above said resilient strip and between said frame and said stationary support, and means operatively connecting said frame 5 and said heel support for moving the heel support transversely by moving the frame transversely.

10. Foot manipulating apparatus including a base, a frame universally mounted on one end of the base, a stationary support on the other end of the base, a resilient foot-supporting strip having one end secured to the frame and the other end slidably mounted in the stationary support, a heel support longitudinally spaced from said 15 frame and independently mounted for transverse movement on the base in a plane perpendicular thereto, and located above said resilient strip between said frame and said stationary support, and means operatively connecting said heel support and said frame for imparting transverse movement to the heel support in a direction opposite to transverse movement applied to the frame.

11. Foot manipulating apparatus including a base, a frame adapted to be located under the 20 front portion of a foot and universally mounted on one end of the base, a stationary support on

the other end of the base, resilient foot-supporting strips adapted to directly support the underside of a foot, said strips being secured at one end in the frame and slidably mounted at their other ends in the stationary support, whereby movement of the frame will flex the resilient strips, a heel support on the base and located over said resilient strips, means for binding the front portion of the foot to said frame, and strap means connected at one end to said frame and 10 at the other end to said heel support for holding a foot in position on the resilient supporting strips and the heel support.

12. Foot manipulating apparatus including a base, a frame mounted on one end of the base 15 for transverse movement in a plane perpendicular thereto thereof, a stationary support on the other end of the base, and a resilient foot-supporting strip adapted to directly support the underside of the foot and secured at one end 20 to the frame and having its other end mounted on the stationary support, whereby said transverse movement of the frame will flex the resilient strip.

JOHN H. McCAHAN.
